CLAIM

The ornamental design for a “support pad for notebook computer”, as shown and described.

DESCRIPTION

FIG. 1 is a front, top, right perspective view of a support pad for notebook computer, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reference perspective view of a notebook computer installed on my new design.

The surface shading lines illustrate contour only and form no part of the present design. The plaid lines illustrate a strap through the support pad which forms no part of the claimed design. The dashed broken lines illustrate environmental subject matter which forms no part of the claimed design.
